CLAIM

The ornamental design for an elastic grip stress reducer in the form of a golf club, as shown and described.

DESCRIPTION

FIG. 1 is a perspective view showing the front, left side and bottom of the elastic grip stress reducer in the form of a golf club showing my new design.

FIG. 2 is a front view thereof.

FIG. 3 is a left side view thereof.

FIG. 4 is a back view thereof.

FIG. 5 is a right side view thereof.

FIG. 6 is a bottom view thereof; and,

FIG. 7 is a top view thereof.
